Primary Examiner — Terry Wallace(74) *Attorney, Agent, or Firm* — Grogan, Tuccillo & Vanderleeden, LLP(57) **CLAIM**

The ornamental design for a chiller, as shown and described.

DESCRIPTION

FIG. 1 is a bottom, front, right side perspective view of a chiller showing our new design;

FIG. 2 is a front elevational view thereof;

FIG. 3 is rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a rear elevational view of an embodiment thereof.

The broken lines of FIGS. 1-8 represent unclaimed portions of the chiller and form no part of the claimed design. The dash-dot-dash broken lines of FIGS. 1-8 represent unclaimed portions of the chiller and form no part of the claimed design, and define boundaries of the claimed design.
